UNITED STATES PATENT OFFICE.

JAMES H. COREY, OF NEW YORK, N. Y.

IMPROVEMENT IN STEAM-VALVES.

Specification forming part of Letters Patent No. 159,019, dated January 26, 1875; application filed November 7, 1874.

To all whom it may concern:

Be it known that I, JAMES H. COREY, engineer, of the city of New York, in the county and State of New York, have invented a new and useful Improvement in Steam-Valves, of which the following is a specification, reference being had to the accompanying drawings, in which—

Figure 1 is a sectional view of a globe and valve united, with one spindle running through and operating both, thus showing my improvement.

Similar letters of reference indicate similar parts.

My invention relates to the construction of steam-valves, intended particularly for use on radiators for heating purposes; and consists in combining a supply and discharge valve, and operating both by a single spindle, so that by turning the latter it opens and closes the top and the bottom valve, the upper valve being for the introduction of steam or water, the lower valve for the discharge of condensation or waste water.

The ordinary custom on radiators or coils of heating-pipes is to have a valve at each end, one being for the admission of steam, the other to carry off the condensation. When two valves are so used, it becomes necessary, for the proper operation of the heating-pipes, to have the valves proportionately opened to each other. As they are generally operated by persons unaccustomed to their use, much trouble is experienced, both in the way of noise from the collection of water in the base, when the valves are not properly arranged, and from a loss of heat and waste of steam in having the purgo too much opened, and allowing the steam to blow through without performing its proper heating functions.

In my valve, by one operation of the spindle, the parts must necessarily always be proportioned to each other—the outlet to the inlet—and the proper opening always be provided for the condensation. The spindle has a waste to it, so as not to leave any water in the radiator.

By the use of my valve, a greater average amount of heat will be obtained from a given amount of steam, the cause of noise in the pipes will be removed, and the apparatus will work as well in the hands of one person as in another. As it will always work properly, economical and beneficial results must ensue.

A is the inlet for the steam. B is the passage for the steam to the radiator-pipes. C is the inlet for the condensation from the radiator-pipes. D is the discharge for the waste water. E is the spindle.

In combining two valves it becomes necessary to pass the spindle through the steam-chamber down to the lower outlet. To prevent the steam from blowing through, the spindle is grooved to form a water-packing where it passes through the sleeves.

This combined valve can be used on any arrangement of pipes where it is desirable to admit steam and get rid of condensation.

The two valves may be kept apart, and stuffing-boxes provided in place of the water-packing, as shown in the drawings, and worked with one spindle.

There are many advantages, however, to its mechanical workings in having the valves attached to each other, as the expansion and contraction of the metals are more equal.

Having thus described my invention, what I claim as new, and desire to secure by Letters Patent, is—

The globe-valve for admitting steam or water, in combination with the discharge-valve, provided with inlet C and discharge D, both valves being operated by a single spindle, E, substantially as and for the purpose set forth.

In testimony whereof I have hereunto signed my name to this specification in the presence of two subscribing witnesses.

JAMES H. COREY.
